H. B. DONLEY

LAMP

Filed April 28, 1924

UNITED STATES PATENT OFFICE.

HAROLD B. DONLEY, OF COLUMBUS, OHIO, ASSIGNOR TO THE JOHN W. BROWN MANUFACTURING COMPANY, OF COLUMBUS, OHIO, A CORPORATION OF OHIO.

LAMP.

Application filed April 28, 1924. Serial No. 709,450.

My invention relates in general to lamps, and more particularly to improvements in the type of lamps which are used on automobiles and for similar purposes.

5 In such lamps as at present constructed it is necessary to remove the lens and lens ring each time a light is changed. This constant removal tends to loosen the connections so that the lens and ring fall off and become 10 broken. The lens ring often becomes rusted to the lamp casing and causes much loss of time in the effort to remove it.

An object of my invention is to provide a head light structure so constructed that the 15 light may be inserted from the rear without removing the lens.

A further object of my invention is to provide a headlight structure in which the bulb and light carrying plug as a unit may 20 be removed and replaced without the trouble or connecting or disconnecting wires.

A still further object of my invention is the provision of a headlight structure which is adapted to be used with either a one wire 25 or a two wire system, both of which are well known.

With these and other objects in view, as will appear as the description proceeds, the invention consists in the novel features of 30 construction, combinations of elements and arrangements of parts hereinafter to be fully described and pointed out in the appended claim.

In the accompanying drawing:

35 Figure 1 is a vertical sectional view of the complete device,

Figure 2 is a sectional view taken on the line 2—2 of Figure 1, and

40 Figure 3 is a sectional view taken on the line 3—3 of Figure 2.

Similar reference characters are used to designate similar parts in the several figures of the drawings.

45 Reference character A indicates the lamp casing which is of the usual construction, being provided with the raised ridge 1 and the annular offset portion 2, which engage the lens ring 3 in the usual manner.

The reflector 4 is secured to the lens ring 3 50 by means of carriage bolts 5 passing through aligned apertures in the ring 3 and in the flange 6 of the reflector 4. The nut 7 is disposed back of the flange 6 and the head of the bolt 5 is rounded, thus insuring that the

bolt 5 can not be removed when the parts are 55 assembled with the casing A.

The flange 8 of the ring 3 bears down upon the lens 9 to hold it firmly against the dust proof packing ring 10 on the shoulder 11 of the reflector 4.

A sleeve 12 is rigidly attached to the reflector 4 at the periphery of a circular aperture in the rear of the reflector 4, and extends therefrom through a similar aperture in the rear wall of the casing A. The free 65 end of the sleeve 12 is externally threaded as at 13 to engage the lock nut 14 which by its engagement with the casing A holds the lens 9, lens ring 3, reflector 4 and sleeve 12, 70 as a unit in assembled relation with the casing A. A cut out portion 15 is provided in the sleeve 12, extending inwardly from the free end thereof for a purpose to be herein-after described.

A plug member 16 is arranged to slide in 75 the sleeve 12. The plug 16 comprises a cylindrical body portion 17, which may be made of any suitable insulating material, in which is embedded the threaded member 18 and the two contact members 19 and 20. 80 Each of these contact members has a portion disposed flush with the outer surface of the plug. The contact member 19 has a reversely bent portion disposed in a cavity in the block which carries the contact point 21 85 to be engaged by the central contact point in the bulb 22.

The socket 23 is secured by screws 24 passing through a flange 25 into the body portion 17 of the plug 16. The socket 23 is provided with the usual bayonet slots to cooperate with the pins on the bulb 22 in the usual manner.

The periphery of the flange 25 is spaced from that of the body portion 17 to provide 90 insulation from the sleeve 12.

The contact 20 passes through the plug and is connected with the socket 23 by means of one of the screws 24.

A terminal block 26 made of insulating 100 material is secured to the casing A and extends slightly into the slotted portion 15 of the sleeve 12.

L shaped contact arms 27 and 28 are moulded into the block 26 and right angular extensions thereof make sliding contact with contacts 19 and 20 respectively on the movable plug 16.

Contact arms 27 and 28 are drilled and tapped to receive the usual screws 29 for securing the wires thereto. In drilling the arm 28, however, the hole is drilled and tapped through the arm 28, the block 26 and the casing A.

This provides a simple means for adapting the headlight for either a one or two wire system. When it is to be used on a one wire system the one wire is connected to the arm 27 and a screw long enough to connect the arm 28 and the casing A is used, thus providing a ground for the one side of the light. When the headlight is to be used with a two wire system the two wires are connected to the arms 27 and 28, a screw being used on the contact 28 which is shorter than the thickness of the block so that it will not ground the contact.

Provision is made for adjusting the position of the bulb with respect to the reflector 4 and comprises a perforated cap 30 secured on the free end 13 of the sleeve 12. A threaded bolt 31 passes through the perforation in the cap 30 and engages the nut 18 of the plug member 16. A collar 32 is provided on the bolt 31 to prevent longitudinal movement of the bolt 31 through the cap 30. The head of the bolt 31 is slotted to accommodate a screw driver or the like for rotating the bolt 31 to move the plug 16 and the bulb 22 with respect to the reflector 4. The provision of sliding contacts on the plug and block makes it unnecessary to bother with wires when changing bulbs and the wires 33 are brought into the rear of the casing A through a bushed aperture 34 and connected to the contacts 27 and 28.

From the foregoing description it will be

observed that I have invented an improved lamp for automobiles and for similar uses in which the illuminating element may be inserted into and removed from the casing without necessitating the removal of the glass front of the casing. It will be further observed that I have provided a headlight structure in which the bulb and socket carrying member may be removed from and replaced in the casing without the trouble of connecting and disconnecting wires.

It will be further observed that I have provided a headlight structure which is adapted to be used with either a one wire or two wire system.

What is claimed is:

In a vehicle headlamp, a casing, a reflector in said casing, a tubular member extending axially from said reflector through an opening provided in the rear wall of said casing, securing means associated with the outer end of said tubular member for uniting the latter with said casing, a closure cap carried by the outer end of said tubular member, a plug of an insulating material longitudinally adjustable in said tubular member, adjusting means carried by said closure and cooperative with said plug to effect the adjustment of the latter from a point exterior of said casing, a bulb socket carried by said plug and adapted for the reception of a lamp bulb of a diameter less than the diameter of said tubular member, bulb contacts carried by said plug, and stationary contacts carried by said casing and arranged for sliding engagement with the contacts of said plug.

In testimony whereof I affix my signature.
HAROLD B. DONLEY.
